UNITED STATES PATENT OFFICE.

AUGUSTIN MARŠÍK, OF PRAGUE, CZECHOSLOVAKIA.

DIRECTION-INDICATING DEVICE ESPECIALLY FOR VEHICLES.

Application filed April 22, 1926, Serial No. 103,932, and in Czechoslovakia April 19, 1925.

For indicating the direction of vehicles it has been proposed to use arrow shaped images which are formed by an aperture in a wall or the like and are provided with 5 points in both directions. In such arrangements the arrow point which it is desired to show the direction to be taken is made prominent either by means of a filling piece pushed behind the other arrow point or by 10 transparent illumination of the specific arrow point. According to another mode of construction the arrows are assembled from mechanical elements. The first arrangement does not insure the rapid and 15 accurate understanding of the given indication, especially by day-light, when the arrow point, which it is desired to make apparent differs only slightly from the remaining one, while the second construction readily gives 20 rise, after a certain wear has occurred, to disturbances and failures. The present invention relates to direction indicating devices, in which the arrow-like images appear in connection with an aperture when 25 a filling piece is displaced or rotated and consists in an unfailing although simple arrangement in which the arrow images are clearly and rapidly recognizable. According 30 to the invention the aperture has the shape of a square, lozenge, hexagon or the like having one of its corners directed to the left and the other corner to the right; the point of the arrow, which normally is 35 invisible is formed only after the filling piece has been displaced or turned, when the contour of this filling piece together with that of the aperture form the image of the arrow point.

In the accompanying drawings are represented in a schematic manner some of the 40 many possible modifications of the invention in its substantial features, while the device which operates the apparatus is not shown. In these examples an element of the 45 image is cut out in the casing of the apparatus or in another stationary part of the same, while the other element of this image is formed by a plate or the like movably mounted in this casing.

50 In the drawings the same reference characters indicate corresponding parts throughout and;

Figures 1 to 3 show front views of a 55 square casing construction, the image element being shown in various positions,

Figs. 4 to 6 are similar views showing

a modified image element construction, and Figs. 7 to 9 show front views of an hexagonal casing construction, the image element being shown in various positions.

Referring first to Figures 1 to 3 a square or lozenge *b* is cut out in the front wall of the square or rhombic casing *a* of the apparatus and forms an element of the image. Closely behind the front wall is mounted a 60 square or lozenge *c*, which is displaceable sideways in both directions and forms the second image element. Under the influence of an external effort, for example operable by the driver's hand, the movable element *c* 65 of the image is displaced for example to the right in such a manner that a part of its contour, that is, the left half of this contour, forms with a part of the stationary image element *b* an arrow 1 Fig. 1. When 70 the element *c* is displaced to the left the lefthand effective lines of the elements *b* and *c* form an arrow 2, Fig. 3. The arrows appear for example white on a dark basis 75 or, if an illumination from behind is employed, they appear luminous on a dark field. When the image element *c* is adjusted in its intermediate position no image at all is visible which indicates a direction which 80 is straight forward.

In the modification shown in Figures 4 to 6 the movable image element is formed by two segments *d* and *e*, which are pivotably mounted on axis *m* and *n* and cooperate in their common pivoting movement. When 85 these segments are rotated to the right an arrow 1, Fig. 4, directed to the left appears and when they are rotated to the left an arrow 2, Fig. 6, directed to the right appears, while in the intermediate position of 90 the segments the image shown indicates a direction which is straight forward.

According to Figures 7 to 9 the stationary element of the image in the front wall of the casing *a* is formed by a hexagon *h* and closely behind the same the movable parts 95 *f* and *g* are arranged, which are provided with a horizontal central slot 3 and form together the movable hexagonal image element. According to the position of these parts *f* and *g* an arrow directed to the left 100 1 or the right 2 or a horizontal line 3 indicating a straight forward direction are formed similarly as in Figures 1 to 3.

These examples show that by a combination of different image elements as to their 105 shape and number different constructive

modifications of the principle of the invention may be carried out. When the invention is applied to a motor car an apparatus may be mounted on the front of the vehicle and another on its rear end without any changes in the construction of the car and both devices may be operated simultaneously by a single lever.

In the above description the expressions "left" and "right" correspond to the figures in the drawing; it is evident that the direction of motion is different for apparatus mounted on the front or rear end of the vehicle. It should be understood that the square, lozenge or hexagonal shapes given as examples in the specification may be replaced by other equivalent shapes without deviation from the spirit of the invention.

Having now described my invention and in what manner the same is to be performed I declare that what I claim is:

1. A direction indicator for vehicles comprising a casing having a cut-out portion in the front wall thereof, said cut-out portion representing by the contour lines portions of arrows for right and left direction indications; and a movable image element in said casing adapted to co-operate with said cut-out portion, said element in a central position relative to the cut-out portion being unindicative of a right or left turn and when moved to the right or left in the casing the cut-out portion and the image element forming a right or left arrow point by means of the contour lines of the cut-out portion of the casing and the image element to indicate a right or left turn.

2. A direction indicator for vehicles comprising a casing having a cut-out portion in the front wall thereof, said cut-out portion representing by the contour lines portions of arrows for right and left direction indications; and a plurality of image segments pivotally mounted in said casing cooperating

with said cut-out portion, said segments in a central position relative to the cut-out portion being unindicative of a right or left turn and when rotated to the right or left in the casing the cut-out portion and the segments forming a right or left arrow point by means of the contour lines of the cut-out portion of the casing and the segments to indicate a right or left turn.

3. A direction indicator for vehicles comprising a casing having a cut-out portion in the front wall thereof, said cut-out portion representing by the contour lines portions of arrows for right and left direction indications; and a pair of image segments pivotally mounted in said casing cooperating with said cut-out portion, said segments in a central position relative to the cut-out portion being unindicative of a right or left turn and when rotated to the right or left in the casing the cut-out portion and the segments forming a right or left arrow point by means of the contour lines of the cut-out portion of the casing and the segments to indicate a right or left turn.

4. A direction indicator for vehicles comprising a casing having a square cut-out portion in the front wall thereof, said cut-out portion representing by the contour lines portions of arrows for right and left direction indications; and a pair of image segments pivotally mounted in said casing in opposite corners relative to the square cut-out portion and cooperating with said cut-out portion, said segments in a central position relative to the cut-out portion being unindicative of a right or left turn and when rotated to the right or left in the casing the cut-out portion and the segments forming a right or left arrow point by means of the contour lines of the cut-out portion of the casing and the segments to indicate a right or left turn.

In testimony whereof I affix my signature.

AUGUSTIN MARŠÍK.
